UNITED STATES PATENT OFFICE.

ADOLF KRAUSS, OF CANNSTATT, GERMANY, ASSIGNOR, BY MESNE ASSIGNMENTS, TO AMERICAN BOSCH MAGNETO CORPORATION, OF NEW YORK, N. Y., A CORPORATION OF NEW YORK

ELECTRIC CONTACT DEVICE.

Application filed August 30, 1917. Serial No. 188,882.

To all whom it may concern:

Be it known that I, ADOLF KRAUSS, a subject of the German Emperor, residing at and whose post-office address is Cannstatt, Brye-
strasse 8, Germany, have invented certain
new and useful Improvements in Electric
Contact Devices; and I do hereby declare
the following to be a full, clear, and exact
description of the invention, such as will
enable others skilled in the art to which
it appertains to make and use the same.

The present invention relates to electric
contact devices and more particularly to
mechanical interrupters for opening and
closing the circuit of an electric ignition
system associated with an internal com-
bustion engine; and the object of the invention
is to provide an electric contact device
of this kind of superior construction and
efficiency.

In accordance with the invention, the me-
chanical interrupter has two separate and
independent springs or spring systems, one
supporting the rigid interrupter lever for
deflection from and to its normal position in
cooperation with the stationary element, and
the other acting as a supplemental spring
continually resisting the deflection of the
lever from its normal position. By thus
providing different springs for these pur-
poses, the possibility of breakage and weak-
ening of the springs is minimized and the
operation of the interrupter is improved.
Preferably, the supporting spring is at-
tached at both ends to the deflectable lever,
and is fastened intermediate of its ends to
a bearing, while the supplemental spring is
attached at one end to the lever and at or
near the other end to a second bearing. The
supplemental spring may project beyond its
bearing into co-operation with the free end
of the interrupter lever to serve as a resili-
ent stop therefor, or a separate spring pro-
jecting from the bearing may be provided
for this purpose.

In the accompanying drawings illustrating
several embodiments of my invention,
Figs. 1, 3, 5 and 7 are plan views of modified
forms of mechanical interrupters; and Figs.
2, 4, 6 and 8 are cross sections thereof.

In the modification shown in Figs. 1 and
2, *a* is the interrupter disc, and *b* is the sta-
tionary contact supported by the insulated
block *c*. The rigid interrupter lever *g* car-

ries the contact *h* at its free end in coopera-
tion with the contact *b*, and carries the fiber
block *i* at its other end for cooperation with
the interrupter cams (not shown). The flat
supporting spring *f* is attached at both ends
to the lever *g*, and is fastened intermediate
of its ends to the bearing *d* mounted on the
disc *a*. The supplemental spring *k* is at-
tached at one end to the lever *g* close to the
fiber block *i*, and is fastened near its outer
end to the bearing *e* mounted on the disc *a*.
The outer end *l* of the spring projects be-
yond the bearing *e* and serves as a resilient
stop for the interrupter lever *g*. In this
modification, the springs *f* and *k* are perfor-
ated and screws passing therethrough hold
them to the respective bearings *d* and *e*.

The rigid interrupter lever *g* carrying
the contact *h*, and the insulated contact *b*
carried by the block *c* are similar in the modi-
fication shown in Figs. 3 and 4 to the cor-
responding parts of the modification shown
in Figs. 1 and 2. Likewise, the supporting
spring *f* is attached at its two ends to the
interrupter lever *g*, and the supplemental
spring *k* is attached at one end to the lever
g. However, the spring *f* is fastened to the
bearing *d* by a gripping device, so that
the spring retains its full strength since it
is not weakened by perforation for the pas-
sage therethrough of a fastening screw.
This gripping device embodies a screw hav-
ing an eccentric body *n* and a threaded por-
tion *p* extending loosely through the inter-
rupter disc *a* into engagement with a nut
p'. After turning the body *n* to grip the
spring *f* tightly between it and the bearing
d, the screw is locked in position by
tightening the nut *p'* thereon.

The two modifications shown in Figs.
5 to 8 are intended to be like those of the
former embodiments, excepting for different
forms of gripping devices for fastening the
supporting spring *f* to the bearing *d*. In
the embodiment shown in Figs. 5 and 6,
the gripping device comprises a tapered or
conical pin *m* forced into the bearing *d*
to tightly grip the spring *f* between it and
the bearing. In the embodiment shown in
Figs. 7 and 8, the screw *p* carries an eccen-
tric sleeve *o*, so that after the sleeve is
turned to a position gripping the spring
f between it and the bearing *d*, the screw
is turned into the nut *p'* until the eccentric

above *a* is rigidly held at its two ends between the top of the bearing and the interrupter disc.

It will be obvious that various other forms of construction may be provided within the invention and that the spring *f* may be fastened to its bearing *d* in various other ways without weakening it by a perforation or a sharp bend. By providing a plurality of springs, one for supporting the rigid interrupter lever for deflection from and to its normal position, and a supplemental spring for resisting the deflection of the lever from its normal position, the duty is distributed between the springs in such a manner that the life and reliability of the interrupter is increased.

Having thus described my invention what I claim is:—

- 23 1. In a mechanical interrupter, a rigid interrupter lever, a spring attached at both ends to the lever, a bearing gripping the opposite surfaces of the spring to support the lever for deflection from and to a normal position, and a supplemental spring continually resisting the deflection of the lever from said normal position.
- 25 2. In a mechanical interrupter, a rigid interrupter lever, an imperforate spring attached at both ends to the lever, a bearing

to which the imperforate spring is attached to support the lever for deflection from and to a normal position, and a supplemental spring continually resisting the deflection of the lever from said normal position.

3. In a mechanical interrupter, a rigid interrupter lever, a spring attached at both ends to the lever, a bearing gripping opposite surfaces of the spring intermediate the ends thereof for supporting the lever for deflection from and to a normal position, and a supplemental spring attached at one end to the lever and fastened to a second bearing for resisting the deflection of the lever from said normal position.

4. In a mechanical interrupter, a rigid interrupter lever, a spring attached at both ends to the lever, a bearing having a tapered pin wedging the spring in position for deflection of the lever from and to a normal position, and a supplemental spring resisting the deflection of the lever from said normal position.

In testimony whereof I affix my signature, in presence of two witnesses.

ADOLF KRAUSS.
